UNITED STATES PATENT OFFICE.

GEORGE LEWIS PRATT, OF ATLANTA, GEORGIA.

MEANS FOR LUBRICATING PULVERIZING-MILLS.

No. 826,059.

Specification of Letters Patent.

Patented July 17, 1906.

Application filed August 14, 1905. Serial No. 274,208.

To all whom it may concern:

Be it known that I, GEORGE LEWIS PRATT, a citizen of the United States, residing at Atlanta, in the county of Fulton and State of Georgia, have invented certain new and useful Improvements in Means for Lubricating Pulverizing-Mills; and I do hereby declare the following to be a full, clear, and exact description of the invention, such as will enable others skilled in the art to which it appertains to make and use the same.

The object of my invention is, generally, to provide a thoroughly efficient and satisfactory means for lubricating certain parts of a machine, such as, say, a pulverizing-mill, which are necessarily in the operation of the machine subjected to intense friction and consequent liability to wear. By my improved antifriction means or means adapted thoroughly to effect lubrication of these parts the durability and strength of the machine as an entirety are greatly lengthened and enhanced and the noise and wear incident to the machines are largely lessened.

With this object in view the invention consists in the novel construction, combination, and arrangement of parts, as hereinafter set forth in the specification, summed up in the claims, and illustrated in the drawings.

It being understood that my improved antifriction means may be employed in any position in any machine where such use may obviously be efficacious, I have shown, merely for sake of illustration in the drawings, my invention applied to a pulverizing-machine and only such parts of such machine as are necessary for a comprehension of the application thereto of my invention.

Referring to the drawings, Figure 1 is a fragmentary central vertical section of a movable roller-carrying table, of one roller and its supporting-shaft, and of a pan adapted for the reception of the material to be pulverized and within which the roller works, my antifriction means being disclosed as applied to such shaft and its supported roller.

Fig. 2 is a detail view of a bearing-disk, thrust-plate, or lubricant-distributing member located at the bottom of the shaft. Fig. 3 is a bottom plan view of a shaft which may be provided with transverse grooves or channels therein, as shown. Fig. 4 is a fragmentary vertical section of an alternate construction. Fig. 5 is a section on line $x-x$, Fig. 4; and Fig. 6 is a section on line B B, Fig. 4.

Referring to the drawings, A designates a

driving-shaft operated in any suitable manner and carrying a roller-supporting table B, to which may be hinged or pivoted a head C, having an internal-threaded opening c. Removably secured in the opening c is a depending shaft D, the upper end of which may be threaded, as shown at d, for this purpose and the lower end desirably enlarged, as at d², which enlarged head is slightly smaller in transverse cross-section than the chamber in which it rests, as shown in the drawings, for a purpose hereinafter appearing. Carried by shaft D at its lower end and prevented from accidental removal therefrom by the enlarged head d² is a roller E, desirably having a neck portion e, which may be threaded at its upper end, as at e². A bushing F, provided with longitudinal grooves k' adjacent the shaft D, (for a purpose hereinafter appearing,) may be placed intermediate roller E and shaft D, and the bushing may be threaded at its upper end, as at f, engaging the threads e^{2x} of a lock-nut e³. Screwed on the bushing F at its upper end may be a bushing-cap, gland, or follower G, provided with internal threads g for this purpose; but any other suitable means may be employed to prevent escape of lubricant at this point. A bottom plate H may be removably secured in any suitable manner to the under side of roller E, as by bolts h and nuts h².

Although not indispensable, I prefer to utilize what I call a "lubricant-distributing member" or "bearing-plate," shaped, preferably, in the form of a circular disk I, which is supported in contact with the under periphery of head d² of shaft D and the upper face of plate H, as shown. This disk may be provided with radial grooves or the like i on either surface thereof in contact with the under face of the head d² or the upper surface of plate H, it being understood that instead of these radial grooves in the disk I, I may provide radial grooves or the like in the under face of the head d² of shaft D, as shown at i², Fig. 3.

Internally of shaft D is a longitudinal channel d⁴, extending through the top to the bottom of the shaft and at its bottom registering with a perforation i³ in disk I. The walls of channel d⁴ are preferably threaded, as at d³, at its upper end for engagement with the threads of a closure-cap N, desirably provided, it being understood that the cap may be screwed down part way only, thus to leave room for escape of lubricant from the

passage M, or any other suitable arrangement for the escape may be used, as desired.

Longitudinal grooves k' and radial grooves k are desirably provided in the bushing F, 5 and grooves k' may communicate at their top with an annular groove L, formed in bushing F. These longitudinal grooves k' may instead be formed in the shaft, if desired, and as this is obvious illustration 10 thereof is deemed unnecessary. In communication, as by by-passage m , with groove L, and consequently with grooves k' , is a discharge-chamber M, formed in and running to the top of shaft D. It is obvious that two 15 or more discharge-chambers M may be formed in the shaft D, and therefore I do not confine myself to the particular disposition shown of such chambers.

Chamber K (in which rests head d^2 of shaft 20 D) may be as large as desired to form a combined storage-compartment and a passage for oil from grooves i to grooves k .

Any suitable force-pump may be used and when used screwed into the upper end of 25 channel d^4 .

In use any suitable kind of lubricant, preferably lubricant in the form of paste and of the consistency, say, of lard, is forced into the channel d^4 , such channel thus constituting a 30 storage-chamber. In the use of the machine the lubricant-paste passes through the radial grooves i of disk I (or through the radial channels on the under surface of the shaft, if such are provided, or through both the channels in disk and in end of shaft, where both sets are provided) into annular passage or 35 chamber K, thence through this chamber into radial grooves k and longitudinal grooves k' into annular groove L, thence into 40 and out of discharge chamber or chambers M, constituting the oil-outlets, thus effecting a most thorough and satisfactory lubrication of all parts subjected to great friction in use and insuring to the machine a maximum of 45 strength and life. As in the operation of the machine the rollers E are preferably rotatable on shafts D, as the rollers may be of great weight, and as the material operated upon may be coarse ore-bearing material to be 50 crushed or pulverized, it is readily seen what a dangerous friction is engendered if no lubricant device were employed and how soon this friction would wear away most important parts of the machine were no such lubricant device provided.

I have found that by my system of storage-chamber d^4 , radial grooves i , passage or chamber K, grooves k and L, and long discharge-outlet M, connected up and operating 55 substantially as described, a machine may run quite an indefinite time before the oil-supply in storage-chamber d^4 needs replenishing.

The efficiency and object of the provision 60 of transverse radial grooves i on both sur-

faces of disk I will be obvious. If grooves i on one side become clogged, the grooves on the reverse side will still be working and the lubricant will work through these, thus preventing clogging of the lubricant at the lower 70 end of the shaft.

In Figs. 4, 5, and 6 I have shown an alternate construction which may be used. In this form the roller (not shown) is preferably fixed on or integral with the shaft Q, (instead of preferably rotatable thereon; as in Figs. 1 to 3,) and the shaft Q is preferably rotatable, (instead of preferably rigid, as in Figs. 1 to 3.) Mounted for rotatable movement in head R, which is hinged or pivoted to roller-supporting table B, Fig. 1, is the said shaft Q, having an annular flange q fitting in a similarly-shaped recess in head R, whereby it is retained therein against downward displacement. A plate q^2 , secured to flange q^3 of head 80 R, prevents upward displacement of the shaft. A cylindrical bushing S, having an upper head s , resting on annular ledge q^4 , internally of head R, may be disposed between shaft Q and head R, a bushing-cap s^2 being desirably secured on the lower end of the bushing. Screwed on upward-extending portion q^5 of plate q^2 may be another cap q^6 . Internally of shaft Q is an oil-inlet channel q^6 , terminating in by-passage q^7 , leading transversely 85 through shaft Q to bushing S. In the bushing S may be vertical or longitudinal grooves s^3 and a lower angular groove s^4 , Fig. 4. The oil may pass down through groove q^6 , thence through groove q^7 , around groove s^4 , and thence up through grooves s^3 to flange q , 90 through grooves T in top of flange s , and thence up through by-passage q^{8x} in flange q , to and through oil-exit channel q^8 in shaft Q, and out. If desired, a ring similar to that 95 shown in Fig. 2 may be employed between the upper surface of head s and the under surface of flange q , this plate being provided with the oil-distributing grooves, as clearly shown in Fig. 2 and described in connection 100 with this figure.

Having thus fully described my invention, what I claim as new, and desire to secure by Letters Patent, is—

1. A shaft carrying a roller, the shaft having an internal longitudinal oil-inlet and storage-channel, and being provided on its under end or bottom surface with transverse, oil-distributing channels communicating with the oil-inlet and storage-channel, and also provided with an internal, longitudinal oil-outlet passage adapted to receive the oil coming from out of the oil-distributing channels in the bottom surface of the shaft. 115

2. The combination with a shaft carrying 120 a roller, the shaft having an internal longitudinal oil-inlet and storage-channel, and transverse oil-distributing channels on its under end or bottom surface communicating 125 with the oil-inlet and storage-channel, of a 130

tom plate secured to the under side of the roller, a member carried between the upper surface of the bottom plate and the bottom surface of the shaft and provided with transverse oil-distributing channels on both of its faces, communicating with the oil-inlet and storage-channel.

15. The combination with a shaft carrying a roller, the shaft having an internal longitudinal oil-inlet and storage-channel, of a bottom plate secured to the under side of the roller, and a circular, disk-shaped member carried between the upper surface of the bottom plate and the bottom surface of the shaft and provided with radial channels communicating with the oil-inlet and storage-channel.

16. The combination with a shaft carrying a roller, the shaft having an internal, longitudinal oil-inlet and storage-channel, of a bottom plate secured to the under side of the roller, a circular, disk-shaped member carried between the upper surface of the bottom plate and the bottom surface of the shaft, and provided with transverse, oil-distributing channels communicating with the oil-inlet and storage-channel, and a bushing disposed between the shaft and the roller and provided with an annular channel therein and also with longitudinal channels communicating at one end with said annular channel and at the other end adapted to receive lubricant coming from out of the said transverse oil-distributing channels in the disk-shaped member; the said shaft being provided with a longitudinal oil-outlet or discharge-passage communicating at its lower end with the said annular channel in the bushing.

17. The combination with a shaft carrying a roller, the shaft having an internal, longitudinal oil-inlet and storage-channel, of a bottom plate secured to the under side of the roller, a circular, disk-shaped member carried between the upper surface of the bottom plate and the bottom surface of the shaft, and provided with transverse, oil-distributing channels communicating with the oil-inlet and storage-channel, a bushing disposed between the shaft and the roller and provided with an annular groove therein, and also with longitudinal channels communicating at one end with said annular channel and at the other end adapted to receive lubricant coming from out of said transverse oil-distributing channels in the disk-shaped member, and a closure-cap secured on the top end of the bushing, the said shaft being provided with a longitudinal oil-outlet or discharge-passage communicating at its lower end with the said annular channel in the bushing.

18. A shaft carrying a roller and having an internal, longitudinal oil-inlet and storage-channel, and having, also, transverse channels therein communicating with said oil-inlet and storage-channel, and also provided with an internal, longitudinal oil-outlet passage adapted to receive the oil coming from out of the transverse channels in the shaft.

In testimony whereof I affix my signature in the presence of two subscribing witnesses.
